5 Claims. (Cl. 29—203)

ABSTRACT OF THE DISCLOSURE

Apparatus for making clip-type electrical connections comprises clip guide or mandrel having a wire-receiving opening therein and clip pusher for pushing a terminal clip over the mandrel, past the opening, and onto a terminal post. A wire tucking means is provided beside the mandrel and is effective to form a bight in an intermediate portion of the wire and tuck the bight into the opening. Severing means in the opening cuts the wire so that when tucking means is thereafter moved out of the opening, the cut end of a wire remains in the opening. Upon subsequent movement of a clip over the mandrel and past the opening, the clip moves against the wire and drags the wire end over the mandrel and onto the terminal post thereby to form a clip-type connection.

This invention relates to apparatus for making clip-type electrical connections between conductors and terminal posts.

The technique of making clip-type electrical connections, as disclosed in the co-pending application of Robert F. Cobaugh, Ser. No. 171,074, filed Feb. 5, 1962, now Patent No. 3,239,918, involves the use of a clip guide or mandrel and a means for pushing a terminal clip over the mandrel and onto the post. When the connection is made, the wire is inserted into an opening in the mandrel so that as the clip is moved over the mandrel, it moves against the wire and drags the wire from the opening, over the mandrel, and over the surface of the post. Various types of hand tools and automatic machines have been designed for making such clip-type connections. When a connection is made with a hand tool, the operator must manually locate the end of the wire in the tool prior to actuating the clip-pushing means to form the connection. The most commonly used automatic wire machine has a mechanism for locating the wire adjacent to the mandrel and in a position such that it will be picked up by the clip. In both types of apparatus, that is in hand tools and automatic wiring machines, the step of positioning the wire properly in alignment with the path of movement of the clip has presented some problems in the past; in automatic wiring machines, relatively complex mechanisms have been required to perform this wire-positioning step while in hand tools, it has been found that the positioning of the wire requires a substantial portion of the time required to make an electrical connection.

The present invention is specifically directed to an apparatus for making electrical connections in which the step of positioning the wire with respect to the mandrel is greatly simplified and can be carried out in a shorter time period than has been possible with previously available devices. It is accordingly an object of the invention to provide an improved method and apparatus for making clip-type electrical connections. A further object is to provide an apparatus in which the wire can be positioned relative to the mandrel of a clip-type electrical connecting apparatus rapidly and accurately. A further object is to provide an apparatus for making clip-type electrical connections which requires a minimum of operator skill. A still further object is to provide an apparatus having

an integral means for severing a conductor extending from a reel which has been previously attached to a first terminal post and which is to be attached to a second terminal post.

5 These and other objects of the invention are achieved in a preferred embodiment in which the apparatus used comprises a mandrel or clip guide having a wire-receiving opening intermediate its ends and a clip-pushing means for pushing a terminal clip over the mandrel and onto the post. The apparatus is also provided with wire-tucking means which is movable into the opening and a wire guide extending parallel to the path of movement of the clip. The wire guide has an outlet disposed adjacent to the opening in the mandrel so that a wire extending from this outlet will be inserted or tucked into the opening upon movement of the tucking means into the opening. A suitable knife or other cutting means is provided in the opening so that when the wire is pushed against this knife, it will be severed in the plane of the cutting edge. In normal usage, the end portion of the wire will extend from the opening of the guide tube and can be tucked into the opening so that it will be in a position to be picked up by the terminal clip upon actuation of the clip-moving means to make an electrical connection with a first terminal post. After this first connection is made, wire drawn from a supply reel through the guide tube to provide a length sufficient to reach to the second terminal post so that the wire will extend from the guide tube and past the opening in the mandrel. The tucking means is then actuated to form a bight in the wire which is pushed into the opening in the mandrel. The wire is severed at the reverse bend of this bight and the tucking means is thereafter moved from the opening. The wire extending rearwardly through the guide tube is carried from the opening by the tucking means leaving the end portion of the lead (formed during severing) extending into the opening. Upon subsequent actuation of the clip-moving means, the severed end of this lead will be electrically connected to the second terminal post.

40 In the drawing:
FIGURE 1 is a side view of one form of apparatus in accordance with the invention;

45 FIGURE 2 is a sectional side view on an enlarged scale of the front portion of the apparatus of FIGURE 1 showing the positions of the parts at the beginning of an operating cycle;

50 FIGURES 3-7 are views similar to FIGURE 2 but showing the positions of the parts at various successive stages of the operating cycle; and

55 FIGURE 8 is a plan view of the clip guide or mandrel of the tool.

55 FIGURE 1 shows a hand tool 2 for making clip-type electrical connections of the general type disclosed in U.S. Patent Nos. 3,186,073 and 3,220,099. The tool 2 differs from the tools in the foregoing U.S. patents in that it incorporates devices for the practice of the present invention. Since the structural features of this type of hand tool are now well-known to the art, only those features of the tool which are necessary for an understanding of the present invention will be described.

60 The tool 2 comprises an outer housing member 4 and an inner housing 6. The outer housing 4 has a depending handle portion 8 while the inner housing 6 has a complementary depending handle portion 10 which is telescopically movable into the handle portion 8. The outer housing 4 has a rectangular rearward extension 12 in which there is provided a stop screw 13 to limit the forward stroke of a clip-pushing member described below. The location of this stop screw is changeable in order to permit adjustment of the stroke limit.

65 An inner frame, contained within the inner housing 6,

has a channel-shaped projection 14 which extends beyond the housing members 4, 6. It will be apparent that the outer and inner housings of the disclosed tool differ from the corresponding members of the tools shown in U.S. Patents 3,186,073 and 3,220,099 in that the housing members of the disclosed tool are shorter than the housing members of the tools shown in the patents. As a result of this difference, a substantial portion of the projecting section 14 of the frame is exposed and a wire-inserting or tucking mechanism 54, described below, is mounted on 10 this exposed end of the housing.

A pair of support plates are mounted against the depending sidewalls of the projecting portion 14 of the frame at the left-hand end thereof, the projecting portion 16 of one of these plates being shown in FIGURE 1. The mandrel block 18 is mounted between the plates 16 and a relatively thin guide plate 20 is mounted centrally within the projection 14 to the right of the mandrel block. A strip of terminal clips 22 is fed over the upper edge of this plate 20 and the leading clip of the strip is broken away from the next adjacent clip by means of a clip pusher 21 which is movable relatively over the head portion of the mandrel and beyond the end of this head portion. A pair of levers 24 are pivotally mounted on the sides of the plate 20 on a pin 26. The left-hand end of the lever 24 shown in the drawing has a finger 27 which is normally lodged against the leading clip of the strip to prevent accidental feeding of the strip. This lever is swung through a slight counterclockwise arc by means of a pin 30 extending between the sidewalls of the left-hand end of the outer housing 4. As explained in the above-identified Patent, 3,220,099, this pin moves relatively past a cam surface 32 on the lever 24 to lower the finger 27 and permit leftward movement of the clip. The lever 24 is normally biased to the position shown in FIGURE 4 by a wire spring 28 bearing against the underside of the lever. Rightward movement of the clip of strips is prevented when the clip pusher is retracted by means of outwardly struck tangs 34 on the upper edge of the plate 20. The lever on the opposite side of the plate 20 is similar to the lever 24 shown and functions in the same manner as the lever 24.

The mandrel extends from the upper side of the mandrel block 18 and comprises a rib portion 38 and a head portion 40 the width of the head portion being substantially equal to, and slightly less than, the distance between the opposed sidewalls of the terminal clip being used. An opening 42 extends downwardly through the head portion and the rib of the mandrel intermediate its ends so that the right-hand portion 40a of the mandrel head extends rightwardly from this opening as viewed in the drawing towards the left-hand end of the plate 20. The leading clip can thus be pushed onto the right-hand end 40a of the mandrel, past and over the opening 42, and beyond the left-hand end of the mandrel head.

Referring to FIGURE 8, it will be noted that while the opening 42 is relatively wide in the direction of the length of the mandrel head, its sides 44, 46 are cylindrical and the edges 48, 50 on the sides of the opening extend towards each other for a substantial distance beyond the cylindrical sidewalls 44, 46. The reason for this construction is to assure that the terminal clip will move over the mandrel head from the portion 40a to the portion 40 thereof and will be supported while it is bridging the gap left by the opening.

A groove 47 is provided on the upper surface of the mandrel head portion 40 and slopes downwardly towards the opening 42 to provide a surface over which the wire core can be drawn while the electrical connection is being made as explained in the above-identified Patent 3,220,099.

A cutting blade 52 is mounted in the floor of the opening 42 and has a cutting edge 53 extending transversely across the opening, preferable at a slight angle with respect to the longitudinal axis of the mandrel. A wire-inserting or tucking mechanism generally indicated at 54 is mounted

on the upper side of the housing projection 14 and comprises a first yoke 56 having depending legs 58 which straddle the projection 14 and are pivoted thereto as shown at 60. An arm 62 extends forwardly from this yoke towards the left-hand end of the tool and has a rod 64 secured to its end. The length of this rod and the length of the arm are such that when the arm is swung about its pivotal axis 60 from the position of FIGURE 2 to the position of FIGURE 3, the rod will move into the opening 42 and against the edge 53 of the cutting blade 52.

A wire guide tube 68 is mounted beneath the arm 62 and has its right-hand end mounted in a second yoke 70 having legs 72 pivotally mounted on the previously identified screws 60. The yoke 70 is straddled by the yoke 56 and is movable independently of this yoke 56 or with the yoke 56 as will become apparent as this explanation proceeds.

A relatively thin head portion 74 of the yoke 70 extends from the upper side of the yoke into a slot 76 in the arm 62. An L-shaped latch member 78 is pivotally mounted in the slot 76 at the left-hand end thereof on a pin 80 and the right-hand edge 82 of this latch conforms to the adjacent edge 84 of the yoke head 74. The arrangement is such that the two yokes 56, 70 can be latched to each other so that they will move in unison when the parts including the latch member 78 are in the positions of FIGURE 3. The yoke 70 can be disengaged from the yoke 56 by merely moving the latch member 78 in a counterclockwise direction to the position of FIGURE 4. It is thus possible to either move the arm 62 upwardly independently of the guide tube 68 or to move the arm 62 and the wire guide tube 68 upwardly as a unit. A leaf spring 86 is provided on the underside of the arm 62 to bias this arm to the position of FIGURE 4 when the two yokes are not latched together, it being understood that the spring will be in a stressed condition when the two yokes are latched together as in FIGURE 3.

In use, the parts will be in the positions shown in FIGURE 2 with the two yokes latched together and with the end 90 of a wire extending from the outlet of the guide tube 68 and alongside the rod 64 at the beginning of the operating cycle. To make an electrical connection between the end 90 of the wire and a first terminal post, herein designated as the A post, the operator first swings the arm 62 downwardly to the position of FIGURE 3 thus moving the end portion 90 of the wire into the opening 42. He then swings the latch 78 in a counterclockwise direction disengaging the yoke 56 from the yoke 70. He then swings the arm 62 upwardly to the position of FIGURE 4. The guide tube 68 will be held in its lowered position by a pair of spaced-apart spring clips 92 mounted on the upper surface of the housing projection 14. The operator can then position the end of the mandrel against the A post and operate the tool to connect the end portion of the wire 90 to this post. During such operation of the tool, the leading terminal clip will be moved over the portion 40a of the mandrel head, against the wire, over the portion 40 of the mandrel head, and onto the post and will drag the wire over the post until a connection, as shown at A in FIGURE 7, is achieved.

The operator then moves the tool to a location adjacent to the second post, the B post, while drawing wire from a suitable supply reel through the guide tube 68. After he has drawn a sufficient supply of wire through the tube, he moves the wire guide tube upwardly until it reaches the position of FIGURE 5 in which it extends parallel to the arm 62 and he then swings the latch member 78 through a slight clockwise arc to latch the two yokes to each other. The operator then swings the arm 62 and the guide tube 68 as a unit through a slight counterclockwise arc until the lower end of the rod 64 enters the opening 42. The lower end of the rod forms a bight in the wire end and pushes this bight into the opening 42 until the reversely turned end portion thereof

is pressed against the cutting edge 53 of the knife at which time the wire will be severed as illustrated in FIGURE 6. The operator then swings the arm and the guide tube upwardly as a unit until they reach the position shown in FIGURE 7 and have been moved out of the way of the clip which will be applied to the B post. The severed end of the wire extending from the A post will remain in the opening 42 and against the side 46 of the opening. The wire is then in a position to be connected to the second terminal post upon actuation of the clip pushing device in the tool. After the wire has been thus connected, the parts are in their proper positions for the initiation of the next operating cycle.

There are several salient advantages of the invention which will be apparent to those who are familiar with clip-type electrical connections. An overall advantage is that the operation of positioning the wire in the mandrel opening is carried out by merely swinging the arm 62 about its pivotal axis and does not require the threading or insertion of the wire into a relatively small opening by the operator. A further advantage is that the step of cutting the wire is combined with the inserting or tucking step so that the operator need not interrupt his motions and use a separate cutting device as was the case with previous tools. From a method aspect, the practice of the invention is advantageous in that the wire is tucked or pushed into the opening by a relatively simple device which moves laterally with respect to the mandrel and to the mandrel opening. A wire-inserting device of this type, and this wire-inserting method, is thus amenable to employment with automatic wiring machines since they involve relatively simple motions of the parts associated with the mandrel head.

Changes in construction will occur to those skilled in the art and various apparently different modifications and embodiments may be made without departing from the scope of the invention. The matter set forth in the foregoing description and accompanying drawings is offered by way of illustration only. The actual scope of the invention is intended to be defined in the following claims when viewed in their proper perspective against the prior art.

I claim:

1. A device for making clip-type electrical connections comprising, a mandrel for guiding individual clips along a predetermined path extending over said mandrel and onto a terminal post, clip moving means for moving a terminal clip along said path, a wire-receiving opening in said mandrel intermediate the ends thereof, a wire guide tube normally extending parallel to said path and towards said mandrel, said guide tube having an outlet adjacent to said wire-receiving opening, means for feeding wire through said guide tube and beyond said opening, wire-tucking means movable laterally of said path and into said opening for tucking a wire emergent from said guide tube into said opening, means in said opening for severing a wire tucked into said opening, and means for moving said guide tube laterally away from said path whereby, the leading end of a wire extending from a substantially endless source through said guide tube can be connected to a first terminal post upon actuation of said tucking means and positioning the end of said wire in said opening, and said wire can be connected to a second terminal post by actuating said tucking means to form a wire bight extending into said opening, sever-

ing said wire at said bight by said severing means, and moving said guide tube laterally away from said path whereby, the wire from said source is moved out of said opening, and the end of the lead formed upon severing of said wire remains positioned in said opening whereby upon movement of a second terminal clip along said path, said end is connected to a second terminal post.

2. In an apparatus for making clip-type electrical connections, said apparatus being of the type comprising a clip guide having a wire-receiving opening therein and means for moving a terminal clip along a predetermined path extending over said guide, past said opening, and onto a terminal post, the improvement comprising, wire-tucking means movable laterally with respect to said opening and into said opening thereby to tuck a wire extending parallel to said path into said opening, and severing means in said opening for severing said wire after tucking when an intermediate portion of said wire is tucked into said opening, said tucking means being operative to position the leading end of a wire in said opening preparatory to connecting said leading end to a first terminal post, said tucking means and said severing means being operative to tuck an intermediate portion of said wire into said opening and sever said intermediate portion preparatory to connecting said wire to a second terminal post.

3. A device as set forth in claim 2 including a wire guide normally extending parallel to said path and having an outlet adjacent to said opening, means for holding said wire guide with its outlet adjacent to said opening, and means for moving said wire guide laterally away from said opening.

4. Apparatus for securing a wire to a terminal member, said wire extending from a substantially endless source, said apparatus comprising a guide member, a wire pick-up device movable along said guide member towards said terminal, said guide member having a recess therein for receiving said wire, wire supply and positioning means adjacent to said guide member, said wire positioning means including a tucking member for tucking a bight of wire into said recess, said positioning means being movable between a first position in which said wire is tucked into said recess and a second position beside said guide member, and cutting means in said recess for cutting said wire at said bight whereby, upon cutting of said wire at said bight and movement of said wire pick-up device, a cut end of said wire is carried towards said terminal.

5. Apparatus as set forth in claim 2 wherein said severing means comprises a cutting edge in said opening, said cutting edge being effective to cut said wire and when said intermediate portion of said wire is forced against said edge by said tucking means.
